JOHN T. PHIPPS, OF HUNTINGTON PARK, CALIFORNIA, ASSIGNOR TO H. C. SMITH MANUFACTURING COMPANY, OF WHITTIER, CALIFORNIA, A CORPORATION OF CALIFORNIA.

CORE DRILL.

Application filed March 11, 1925. Serial No. 14,688.

This invention relates to core drills for taking cores of formations to be drilled for oil, water and other wells, which cores are taken so that the log of the well may accurately reflect the formations through which the well is produced. The invention has for its object to provide an improved core drill which, together with the core-receiving tube, may readily be assembled with or applied to a tubular drill stem and its collar, and the parts and features of which are so constructed, formed and applied that substitution of fresh parts or dressed drill members may readily be made, and the core-receiving tube with its core may readily be removed from the drill stem for removal of the core.

The invention has for further objects the provision of an improved core drill construction and organization which will be superior in point of simplicity and inexpensiveness, taken together with durability, facility in use, adjustment, replacement, repair and dressing of the cutting portions, and positiveness, efficiency and speed in use and operation.

With the above and other objects in view, the invention consists in the novel and useful provision, formation, construction, combination, association and relative arrangement of parts, members and features, all as hereinafter described, shown in the drawing and finally pointed out in claims.

In the drawings:

35 Figure 1 is a fragmentary and partly sectional side elevation of a drill stem and core-receiving tube assembled, with core drill features constructed and organized to embody the invention in one form;

40 Figure 2 is an enlarged bottom plan view of the drill shown in Fig. 1.

Figure 3 is a vertical transverse sectional view taken upon the line 3—3, Fig. 2;

45 Figure 4 is a similar view taken upon the line 4—4, Figure 2;

Figure 5 is an enlarged side elevation of the lower portion of the construction shown in Figure 1;

50 Figure 6 is a perspective view of a core tube bushing shown in the other figures;

Figure 7 is a perspective view of a core breaker shown in the other views;

Figure 8 is a bottom plan view of a core cutter shown in the other figures; and,

Figure 9 is a side elevation of such core cutter as shown in Figure 8.

Figures 2 to 9 inclusive are drawn to the same scale.

Corresponding parts in all the figures are designated by the same reference characters.

Referring particularly to the drawings, I have shown at A a drill stem provided with a male member "a" of a tapered threaded tool joint, whereby such drill stem may be connected with a string of drill tools or drill tubing.

This tubular drill stem is provided at the lower end with a drill collar 10, preferably produced by enlarging the drill tube, and this drill collar is vertically slotted, there being preferably three such slots formed, as at 11, for the initial reception of an annular bushing 12 provided with a plurality of radial external heads or bosses 13 respectively received by and within the slots 11, so that the bushing 12 fits up within the drill collar 10, and, being shouldered as at 13^a and threaded internally above such shoulder, as at 13^b, receives in threaded union the lower end portion of the core tube B, which is first passed upwardly within the drill stem, prior to introduction of the bushing 12, as mentioned. The core breaker C is annular in form and provided with a plurality of inwardly and upwardly inclined core breaking teeth 14, which may be produced by punching the metal of the annulus C inwardly, and this annulus or breaker ring C is positioned within the drill collar 10 beneath the bushing 12 and brought into position to abut against the same, such breaker annulus being of slightly larger internal diameter than the internal diameter of the lower portion of the bushing 12, which lower portion is slightly diminished to produce a downwardly tapering bore for the retention of the core at its lower end.

The cutters D are then inserted upwardly into the lower portion of the tubing collar 10, said cutters each having a segmental body 100

- 15 provided with an external radial head 16 adapted to be received within one of the slots 11 in abutting engagement against the respective head 13 of the annular bushing 12. Each such head has its lower end formed to provide a reaming cutter having a transverse cutting edge portion 16^a at its lower extremity extending to the inner periphery of the body 15. Dovetail heads 16^a are held in dovetail recesses 16^d in the collar 10, at abutting ends of the segmental bodies 15, firmly holding the cutters D in place. The lower edge of each such cutter section is provided with a plurality of cutting teeth 16^b having transverse cutting edges 16^b which are arranged in a series in the arc of a circle having the same generating center as the arc in which lie the cutting edges 16^a, the largest arc described by the cutting edges 16^b having a lesser radius than the arc described by the outer cutting portions of the edge 16^a. These cutting edges 16^b thus constitute lower terminal portions of the segment 15. All of the cutting edges 16^a and 16^b lie in the same plane transversely of the segment 15. The drill stem is provided with a circular passage 17, preferably co-axial with the drill stem A, and in the upper portion thereof, and extending through the joint member "a" whereby fluid may be circulated down through the drill stem and outwardly through longitudinal circulation passages 18 at the lower end of the drill collar 10, to provide fluid for the cutters D.
- 35 The heads or bosses 13 upon the bushing 12 are provided each with a vent passage 13^c communicating with the interior of the bushing 12, and the interspace between it and the core tube B and the core itself, which latter 40 is indicated at E. At the top of the core tube B is a vent controlled by a ball check valve 19 within a cage 20, which is normally seated, but may be unseated by air pressure within the core tube, to permit air displacement upon the introduction of the core within the tube, or displacement of water or any other medium therein. This check valve, however, serves to prevent flooding of the core tube with the fluid supplied through the circulation passage 17. If, however, the tube becomes so flooded, the vents 13^c discharge such fluid matter from the tube. These vents likewise permit displacement of air or other media from the core tube upon the introduction of the core, making entrance of the core with the tube easier; and in case the check valve 19 becomes clogged or obstructed drainage of the tube may take place through such vents.
- 50 There are a plurality of the cutter segments D employed, and they, together with the collar 10, breaker annulus C and the bushing 12 are held in place in the following manner: The cutter sections 15 are internally enlarged to produce shoulders 15^a upon

which rests the core breaker annulus C, said breaker annulus being inserted into the collar 10 with the cutter sections 15 or before said cutter sections are inserted. This breaker annulus C has an opening 21 through which headed bolts 22, one at a time, may be passed, the shanks of such bolts being passed through bores or perforations 23 in the drill collar 10, and the heads being received within chambers or pockets 24 in the respective adjacent cutter sections 15. Nuts 25 are applied to the outer threaded ends of the bolts 23, externally of the drill collar 10.

The method of use and operation of a core drill mechanism or device constructed and organized to practice the invention will be readily understood from the foregoing description, taken in connection with the accompanying drawings. However, it may be added that when the parts are assembled, as shown in Figures 1, 2, 3, 4 and 5, the drill stem is operated through the drill string from the mouth of the bore, and the cutting edge portions or teeth 16^a and 16^b enter the earth formation and produce a bore of a diameter greater than that of the enlarged drill collar 10, inasmuch as the heads 16^a upon the cutters or cutter segments 15 extend radially outwardly of the periphery of the drill collar 10. As the earth formation is cut away and the cuttings or detritus or "mud" is removed by the circulation system including the bore 17, the drill stem A and the passages 18, so that the spoil from the bore passes out at the surface of the bore of the drill string, the core is produced within the field of the action of the cutting edges of the cutter segments. This core progressively produced in this manner passes upwardly within the cutters, the core breaker, the bushing 12 and the core tube; and, when it is desired to withdraw the core, pulling of the drill string or tubing causes the breaker teeth 14 to bite into the core and sever the portion above such teeth which is retained by such teeth and the lower contracted portion of the bushing 12, so that the core is withdrawn from the bore within the core tube and the tubular drill stem. The core breaker C also acts as an anti-friction ring between the core and the cutters, particularly in the starting of the coring action, the core being engaged by the teeth 14 in the rotation of the drill stem and cutters, and turning with the teeth, the annulus of the core breaker thus turning within the cutter segments, and, with said teeth, holding the core away from the cutters, and out of any material frictional contact with the inner face of the bushing 12. The enlarged lower portion of the bushing provides an internal core chamber within the tube B having an inner diameter greater than the diameter of the core, so that no material

friction of the core in engagement with the inner walls of the core tube occurs. The cutters D, with breaker and bushing 12 may readily be removed from the drill stem and 5 drill tube, freeing the core.

It is obvious that various and extensive changes and modifications in construction, formation, adaptation, assemblage and combination and association of parts, members 10 and features may be made, and indulged in, in variation and distinction from the foregoing description and statement, and the disclosure of the accompanying drawings, in adapting the improvements to varying conditions of use and service, without departing 15 from the true spirit of the invention.

Having thus disclosed my invention, I claim and desire to secure by Letters Patent:

20 1. Improvements of the character disclosed, comprising a tubular drill body, and a core tube within the same, means being provided for retaining the core tube against vertical movement within the drill body and 25 in driving relation thereto and removable at the bottom thereof, said means comprising a detachable member applied within the bottom of the drill body, said detachable member having a vent communicating with 30 the interior of the core tube and leading to the exterior of the drill body above its lower end.

2. Improvements of the character disclosed, comprising a tubular drill body, and 35 a core tube within the same, means being provided for retaining the core tube against vertical movement within the drill body and in driving relation thereto and removable at the bottom thereof, said means comprising a detachable member applied within the bottom of the drill body, said detachable member having a vent communicating with the interior of the core tube and leading to the exterior of the drill body above its lower 40 end, said core tube having a valve opening 45 at the upper end thereof.

3. Improvements of the character disclosed, comprising a tubular drill body, and a core tube within the same, means being provided for retaining the core tube against vertical movement within the drill body and 50 in driving relation thereto and removable at the bottom thereof, said means comprising a detachable member applied within the bottom of the drill body, said detachable member having a vent communicating with the interior of the core tube and leading to the exterior of the drill body above its lower 55 end, said drill body having a circulation passage at the upper end portion thereof.

4. Improvements of the character disclosed, comprising a tubular drill body, and a core tube within the same, means being provided for retaining the core tube against 60 vertical movement within the drill body and

in driving relation thereto and removable at the bottom thereof, said means comprising a detachable member applied within the bottom of the drill body, said detachable member having a vent communicating with the 70 interior of the core tube and leading to the exterior of the drill body above its lower end, said core tube having a valve opening at the upper end thereof, said drill body having a circulation passage at the upper 75 end portion thereof.

5. In improvements of the character disclosed, a tubular drill body, a core tube within the drill body, and a bushing within the drill body below said tube and connecting 80 the lower end of the core tube with the drill body, said bushing being provided with a laterally disposed vent communicating with the interior of said bushing and leading to the exterior thereof above its lower 85 end.

6. In improvements of the character disclosed, a tubular drill body, a core tube within the drill body, and a bushing within the drill body and beneath the core tube, said 90 drill body being slotted at its lower portion between the interior and exterior thereof, and said bushing being provided with radial extensions received within said slots.

7. In improvements of the character disclosed, a tubular drill body, a core tube within the drill body, and a bushing within the drill body and beneath the core tube, said drill body being slotted at its lower portion between the interior and exterior thereof, 100 and said bushing being provided with radial extensions received within said slots, means being provided for holding said bushing detachably in position.

8. In improvements of the character disclosed, a tubular drill body, a core tube within the drill body, and a bushing within the drill body and beneath the core tube, said drill body being slotted at its lower portion, and said bushing being provided with radial 110 extensions received within said slots, vents being formed in said radial extensions.

9. In improvements of the character disclosed, a tubular drill body, a core tube within the drill body, a bushing within the drill body connecting the lower end of the core tube to the drill body, and a core breaker within the drill body beneath the bushing. 115

10. In improvements of the character disclosed, a tubular drill body, a core tube within the drill body, a bushing within the drill body connecting the lower end of the core tube to the drill body, and a core breaker within the drill body beneath the bushing, means being provided for retaining said 120 mentioned features detachably in assemblage.

11. In improvements of the character disclosed, a tubular drill body, a core tube within the drill body, a bushing within the drill 130

- body connecting the lower end of the core tube to the drill body, and a core breaker within the drill body beneath the bushing, a cutter being applied to the drill body beneath said bushing, means being provided for holding said mentioned features detachable in assemblage.
12. In improvements of the character disclosed, a tubular drill body, a core tube with-
10 in the drill body, a cutter having an upper portion extending axially into the drill body and supporting the core tube in rigid relation with said drill body, and a core breaker supported by the cutter beneath the core tube.
13. In improvements of the character disclosed, a tubular drill body, a core tube with-
20 in the drill body, and a cylindrical cutter adapted to be inserted upwardly within the drill body to support the core tube and provided with external radial projections ex-
25 tended upwardly within slots in the lower end portion of the drill body and extending between the interior and exterior of said body.
14. In improvements of the character disclosed, a tubular drill body, a core tube with-
30 in the drill body, and a cylindrical cutter comprising segmental sections adapted to be inserted upwardly within the drill body to support the core tube and provided with external radial projections extended up-
35 wardly within slots in the lower end portion of the drill body, there being a bushing within the drill body and with which the lower end of the core tube is detachably connected, said bushing having radial projections like-
40 wise entered within said slots.
15. In improvements of the character disclosed, a tubular drill body, a core tube with-
45 in the drill body, and a cutter segment adapted to be inserted within the drill body beneath the core tube and provided with ex-
50 ternal radial projections received within slots in the lower end portion of the drill body, there being a bushing within the drill body with which the lower end of the core tube is detachably connected, said bushing having radial projections like-
55 wise entered within said slots, said radial projections having vents leading to the interior of the core tube.
16. In improvements of the character disclosed, a drill body having a central bore and an arcuate cutter body fitting within the bore of said drill body and provided with a radial extension extended outwardly within a slot in the lower portion of the drill body, said radial extension being formed at its lower extremity into a cutting edge.
17. In a core drill the combination of: a tubular drill body having axial openings in the wall thereof extending up a short dis-
60 tance from the lower end of said body; a core tube adapted to be extended upwardly
- into said body; a bushing secured to the lower end of said core tube; projections pro-
vided upon said bushing which are received by said openings when said core tube is in-
serted in said body; and a cutter member adapted to be inserted upwardly into the lower end of said body to engage in said openings and be secured therein to retain said bushing in place.
18. In a core drill the combination of: a 75 tubular drill body having axial openings in the wall thereof extending up a short dis-
80 tance from the lower end of said body; a core tube adapted to be extended upwardly into said body; a bushing secured to the 85 lower end of said core tube; projections pro-
vided upon said bushing which are received by said openings when said core tube is in-
90 serted in said body, said projections having vents formed therein which communicate be-
95 tween the lower end of a core chamber, formed within said core barrel and said bushing and the exterior of said drill body; and cutting means secured to the lower end of said body in such manner as to hold said 100 bushing in place.
19. In a core drill the combination of: a tubular drill body having axial openings in the wall thereof extending up a short dis-
105 tance from the lower end of said body and from the inner to the outer surfaces of said body; a core tube adapted to be extended upwardly into said body; a bushing secured to the lower end of said core tube; projec-
110 tions provided upon said bushing which are received by said openings when said core tube is inserted in said body; and a cutter member adapted to be inserted upwardly into the lower end of said body to engage in said openings and be secured therein to 115 retain said bushing in place.
20. In a core drill the combination of: a tubular drill body having axial openings in the wall thereof extending up a short dis-
120 tance from the lower end of said body and from the inner to the outer surfaces of said body; a core tube adapted to be extended upwardly into said body; a bushing secured to the lower end of said core tube; projec-
125 tions provided upon said bushing which are received by said openings when said core tube is inserted in said body, said projections having vents formed therein which communicate 130 between the lower end of a core chamber formed within said core barrel and said bushing and the exterior of said drill body; and cutting means secured to the lower end of said body in such manner as to hold said bushing in place.
21. In a core drill the combination of: a 125 tubular drill body having axial openings in the wall thereof extending up a short dis-
130 tance from the lower end of said body and from the inner to the outer surfaces of said body; a core tube adapted to be extended

upwardly into said body; a bushing secured to the lower end of said core tube; projections provided upon said bushing which are received by said openings when said core tube is inserted in said body; a cutter member adapted to be inserted upwardly into the lower end of said body; projections formed upon said cutter member which are received by said body openings beneath said bushing 5 projections; and means for holding said cutter member in place in said drill body.

22. In a core drill the combination of: a tubular drill body having axial openings in the wall thereof extending up a short distance from the lower end of said body and between the interior and exterior thereof; a core tube adapted to be extended upwardly into said body; a bushing secured to the lower end of said core tube; projections provided upon said bushing which are received by said openings when said core tube is inserted in said body; a cutter member adapted to be inserted upwardly into the lower end of said body; projections formed upon 10 said cutter member which are received by said body openings beneath said bushing projections; means for holding said cutter member in place in said drill body, there being a core breaker recess formed in said cutter member; and a core breaker adapted to be retained in said recess.

23. In a core drill the combination of: a tubular drill body having axial openings in the wall thereof extending up a short distance from the lower end of said body; a core tube adapted to be extended upwardly into said body; a bushing secured to the lower end of said core tube; projections provided upon said bushing which are received by said openings when said core tube is inserted in said body; an annular cutter member formed of arcuate sections abutting together, abutting faces of said sections having openings; and studs adapted to be inserted in said openings when said cutter member is disposed upwardly in the lower end of said drill body, and engage the wall of said body to retain said core tube, bushing and cutter member in assembly with said tubular drill body.

24. In a core drill the combination of: a tubular drill body having axial openings in the wall thereof extending up a short distance from the lower end of said body and between the interior and exterior thereof; a core tube adapted to be extended upwardly into said body; a bushing secured to the lower end of said core tube; projections provided upon said bushing which are received by said openings when said core tube is inserted in said body; a cutter member adapted to be inserted upwardly into the lower end of said body; projections formed upon said cutter member which are received

by said body openings beneath said bushing 65 projections, said cutter projections forming the major cutting teeth of said core drill; and means for holding said cutter member in place in said drill body.

25. In a core drill the combination of: a tubular drill body having axial openings in the wall thereof extending up a short distance from the lower end of said body; a core tube adapted to be extended upwardly into said body; a bushing secured to the lower end of said core tube; projections provided upon said bushing which are received by said openings when said core tube is inserted in said body; an annular cutter member adapted to be inserted upwardly 70 in the lower end of said drill body so as to hold said bushing in place, said cutter member having sectors so formed as to provide securing openings at the points of their meeting; minor cutting teeth provided upon 75 the lower edges of said sectors; major cutting teeth extending from said sectors so as to fit into said axial drill body openings; and means for securing said cutter member in said drill body, said means extending into 80 said securing openings.

26. In a core drill the combination of: a tubular drill body having axial openings in the wall thereof extending up a short distance from the lower end of said body; a core tube adapted to be extended upwardly 95 into said body; a bushing secured to the lower end of said core tube; projections provided upon said bushing which are received by said openings when said core tube is inserted in said body; an annular cutter member formed of arcuate sections abutting together, abutting faces of said sections having 100 openings; studs adapted to be inserted in said openings when said cutter member is disposed upwardly in the lower end of said drill body, and engage the wall of said body to retain said core tube, bushing and cutter member in assembly with said tubular drill body, there being a core breaker 105 recess formed in said cutter member; and a core breaker adapted to be retained in said recess.

27. In a core drill the combination of: a tubular drill body having axial openings in 115 the wall thereof extending up a short distance from the lower end of said body; a core tube adapted to be extended upwardly into said body; a bushing secured to the lower end of said core tube; projections 120 provided upon said bushing which are received by said openings when said core tube is inserted in said body; an annular cutter member adapted to be inserted upwardly in the lower end of said drill body so as to hold 125 said bushing in place, said cutter member having sectors so formed as to provide securing openings at the points of their

meeting; minor cutting teeth provided upon the lower edges of said sectors; major cutting teeth extending from said sectors so as to fit into said axial drill body openings; ⁵ means for securing said cutter member in said drill body, said means extending into said securing openings, there being a core

breaker recess formed in said cutter member; and a core breaker adapted to be retained in said recess. ¹⁰

In testimony whereof, I have signed my name to this specification.

JOHN T. PHIPPS.
